UNITED STATES PATENT OFFICE.

OLIVER BRYAN, OF NEW YORK, N. Y.

HOT-AIR FURNACE.

SPECIFICATION forming part of Letters Patent No. 234,282, dated November 9, 1880.

Application filed September 23, 1880. (No model.)

To all whom it may concern:

Be it known that I, OLIVER BRYAN, of the city, county, and State of New York, have invented a new and useful Improvement in 5 Hot-Air Furnaces, of which the following is a specification.

Figure 1 is a sectional plan view of the improvement. Fig. 2 is a sectional side elevation. Figs. 3 and 4 represent modifications of the 10 tiles.

Similar letters of reference indicate corresponding parts.

The object of this invention is to furnish hot-air furnaces so constructed that the air 15 when heated will be pure; that the heating-surfaces can be readily inspected and cleaned; that the fire will act instantly and uniformly upon all the heating-surfaces, making the expansion thereof equal and the radiation of 20 heat quick and regular.

The invention consists in a hot-air furnace having front, side, rear, and top walls, a grate surrounded by upwardly-projecting tiles to form a fire-box, vertical angular tiles having 25 flat tiles upon their upper ends, horizontal angular tiles, a rear wall to separate the combustion-chamber from the hot-air chamber and form a large amount of heating-surface, and a wide smoke-flue, whereby the smoke can be 30 taken out at any convenient point, all constructed and operating as will be hereinafter fully described.

A represents the brick bottom, B the front wall, C the side wall, and D the rear wall, of 35 the furnace. In the front wall, B, is formed a feed-opening, E, a poke-hole, F, and an opening, G, into the ash-pit H, all of which openings are designed to be furnished with doors in the ordinary manner. The sides of the 40 feed-opening E are formed of tiles I, and its top and bottom of iron castings J.

K is the fire-grate, which rests upon the walls L of the ash-pit H, and has upwardly-projecting tiles M at its sides and inner end, 45 forming the fire-box.

The sides and top of the combustion-chamber N are formed of angular tiles O, of burned clay, made with closed ends. The side tiles, O, are placed vertical, with their lower ends 50 resting upon the brick bottom A of the furnace, and with their angles outward. The ad-

jacent edges of the tiles O are beveled to fit squarely against each other, are grooved longitudinally to receive a burnt-clay key, P, and the joints are made tight with clay cement, so 55 that they will not be liable to open and allow smoke and gas to enter the hot-air chamber Q and contaminate the hot air.

If desired, the tiles O may be made with flanged edges to interlock with each other, as 60 illustrated in Fig. 3; or the tiles may be made in the form of boxes having three sides, or they may be corrugated, the object being to obtain a large amount of heating-surface in a small space.

Upon the upper ends of the side tiles, O, are laid flat tiles R, upon which are laid the top or roof tiles, O. The top tiles, O, are laid with their angles upward, and their adjacent edges are beveled and keyed and cemented to 70 each other, or otherwise connected, as herein-before described with reference to the side tiles.

The rear end of the combustion-chamber N is formed of a brick wall, S, to which the edges 75 of the adjacent tiles O are keyed and cemented.

The rear wall, D, of the furnace is made double to form a smoke-flue, T, extending the entire width of the hot-air chamber Q, so that the rear wall of the furnace will be evenly 80 heated, and so that the smoke can be taken to the chimney from any part of the said flue T, as the relative positions of the furnace and chimney may render most convenient. The smoke-flue T is connected with the lower rear 85 part of the combustion-chamber N by one or more flues, U, leading in through the inner part of the rear wall, D, through the rear part of the hot-air chamber Q, and through the rear wall, S, of the combustion-chamber N. The 90 flues U are extended through the rear part of the rear wall, D, to form cleaning-flues V. The outer ends of the cleaning-flues V are closed with doors.

The top of the furnace is covered with bricks 95 W, supported by iron girders. The hot air is conducted to the rooms to be heated through pipes inserted in openings in the top wall, W, or in the side walls, C, which pipes are not shown in the drawings.

Cold air to be heated is introduced into the forward or other convenient part of the hot-

air chamber Q through suitable openings, as indicated in dotted lines in Fig. 1.

The feed-opening E and the combustion-chamber N are designed to be made so large that an attendant can readily enter the combustion-chamber N and clean and brush off the heating-surface.

Having thus fully described my invention, I claim as new and desire to secure by Letters

10 Patent—

1. A hot-air furnace constructed substantially as herein shown and described, consisting of the walls B C D W, the grate K, and tiles M, forming the fire-box, and the angular tiles O, the flat tiles R, and the wall S, sepa-

rating the combustion-chamber and the hot-air chamber, and the smoke-flues T U, as set forth.

2. In a hot-air furnace, the combination, with the walls B C D and the fire-box K M, of the angular tiles O, jointed to each other, the flat tiles R, and the wall S, substantially as herein shown and described, whereby the combustion-chamber N and the hot-air chamber Q are separated from each other and a large heating-surface is obtained, as set forth.

OLIVER BRYAN.
